DESCRIPTION OF THE PREFERRED EMBODIMENT

Description is first made on voltage stabilizers according to the prior art for facilitating the understanding of the present invention.

FIG. 1 shows a simple bimetal-type voltage regulator indicated in block A, which comprises contacts 1, a bimetal strip 2, a heater wire 3, a resistance wire 4, an indicator formed of a bimetal strip 5, a thermistor 6, an

input terminal 7, an output terminal 8, and a grounded terminal 9. Output is derived from the output terminal 8. Voltage regulators of this type have such a drawback that they often cause malfunction and have poor service life.

There have been also proposed transistor-type voltage stabilizers in which said contacts 1 are reformed or modified in contactless continuous type, such as shown in FIG. 2. The voltage stabilizer shown in FIG. 2 comprises a transistor 10, a resistor 11, a Zener diode 12, and a diode 13. An output is derived from the output terminal 8. Voltage stabilizers of this type have such a drawback that the power consumption in the transistor 10 is large and thus requires a larger power transistor which increases costs.

Now, description is made on the embodiment of the present invention shown in the drawings.

In the embodiment of FIG. 3, a voltage stabilizer (regulator) is indicated by A and includes a switching circuit B and a constant current circuit C for stabilizing an input current of the switching circuit B. The constant current circuit C consists of a resistor 14, a Zener diode 15, and a transistor 16. An output transistor circuit 10 consists of a Darlington connection of two transistors 10a and 17 and is controlled by the circuit consisting of a Darlington connection of two transistors 18 and 19. Numerals 20 and 21 are biasing resistors. A level shifting circuit D is formed of level-shifting diodes 22, 23 and 24 and a transistor 25. A switching voltage detecting circuit E is formed of a Schmitt circuit comprising two transistors 27 and 28, two collector resistors 26 and 29, and a common emitter resistor 30. Further, a temperature compensating circuit F is formed of a transistor 32 provided with an emitter resistor 31, two diodes 33 and 34, and two bias resistors 35 and 36. An impedance transforming circuit G for detecting voltage G is formed of a Darlington connection of two transistors 37 and 38 provided with an emitter resistance 39, and forms an emitter-follower circuit for the above-mentioned Schmitt circuit. An output voltage compensating circuit H is formed of a diode 40, four resistors 41, 42, 43 and 44, and a capacitor 45. Here, the switching circuit B can be formed by various methods.

The operation of the present device will be described with respect to the above structure. A charging current is allowed to flow by a voltage appearing at the output terminal 8 through the diode 40 and the resistor 41 in the output voltage compensating circuit H to the capacitor 45. When the voltage of this capacitor 45 reaches a predetermined value, the transistor 28 of the switching voltage detecting circuit E becomes conductive and this transistor 27 becomes of a high level, i.e., its cut-off state. Then, through the level shifting circuit D including the three diodes 22, 23 and 24 and the transistor 25, the voltage at the interconnection of the resistors 20 and 21 is increased and the transistors 18 and 19 connected in Darlington connection are turned into their conductive states. Thus, the output transistor circuit 10 is rendered to be cut off.

When the output transistor circuit 10 is cut off, the voltage at the output terminal 8 becomes zero. Then, in the output voltage compensating circuit the capacitor 45 discharges through two resistors 42 and 43. When the voltage across the capacitor 45 decreases below a predetermined value, said switching voltage detecting circuit E is reversed and the output transistor circuit 10 returns to the conductive state.

The above cycle is repeated. Thus, a DC voltage applied to the input terminal 7 is transformed into a square-wave output having a stabilized effective voltage, which operates the load resistor 4, the indicator 5 formed of a bimetal strip and the thermistor 6, with high precision.

Further, the line voltage (power source voltage) for said switching voltage detecting circuit E is fixed by the constant current circuit C comprising the resistor 14, the Zener diode 15 and the transistor 16. Therefore, it does not vary even when a DC voltage applied between the terminals 7 and 9 is varied. Further, the temperature compensation of this switching voltage detecting circuit E can be achieved by the temperature compensating circuit F in which the forward voltage drop of the two diodes 33 and 34 varies depending on the temperature and hence the base current of the transistor 32 is varied to achieve the temperature compensation. Further, the emitter-follower circuit G comprising two transistors 37 and 38 and the emitter resistor 39 functions to isolate the impedance on the Schmitt circuit side from that on the output voltage compensating circuit side and accordingly, the impedance on the switching voltage detecting circuit E side does not influence the charging and discharging time constant of the capacitor 45 in the output voltage compensating circuit H.

Next, the constancy of the effective-voltage of the square-wave output will be discussed in detail referring to the electrical connection diagram of FIG. 5 of the present voltage stabilizer provided with an output voltage compensating circuit H in comparison to the electrical connection diagram of FIG. 4. The effective-voltage of the present voltage stabilizer will be calculated. It is assumed that the voltage between input terminals 7 and 9 is V (volts), the resistances of the five resistors 41, 42, 43, 44 and 47 are R (ohms), r_1 (ohms), r_2 (ohms), ρ (ohms) and r (ohms), the capacitance of the capacitor 45 is C (Farads), that the switching circuit B drives the output transistor circuit 10 to be cut off when the voltage at a terminal 48 is V_o (volts) and to be conductive when the voltage at the terminal 48 is $(V_o - \Delta V)$, and that $V_o \gg \Delta V$ and the saturation voltage of the output transistor 10 and the voltage drop in the diode 40 are negligible.

First, the effective-voltage at the terminal 8 of the voltage stabilizer of FIG. 4 $V_{eff,1}$ is calculated. If the time periods during which the output transistor circuit 10 is conductive and cut off are set t_{on} and t_{off} as shown in the output voltage waveform of FIG. 6, respectively,

$$V_{eff,1} = \sqrt{t_{on}/t_{on} + t_{off}} \cdot V^2 = V \cdot \sqrt{t_{on}/t_{on} + t_{off}} \quad (1)$$

The charging current I_{cl} flowing into the capacitor 45 when the voltage at the terminal 48 is in the neighborhood of V , is

$$I_{cl} \approx (1/R) V - (1/R + 1/r) V_o \quad (2)$$

provided that the output transistor circuit 10 is conductive. Further, the discharging current I_{d1} flowing from the capacitor 45 when the output transistor circuit 10 is cut off, is

$$I_{d1} \approx (1/R + 1/r) \cdot V_o \quad (3)$$

provided that a resistor of a sufficiently small resistance compared to R is connected between the terminals 8 and 9. Here, t_{on} and t_{off} are the time periods required for the voltage at the terminal 45 to rise from $(V_o - \Delta V)$ to V_o and to drop from V_o to $(V_o - \Delta V)$ by the charge and discharge of the capacitor 45. In this case, ΔV is sufficiently small in comparison to V_o and thus

$$V_o - (V_o - \Delta V) = 1/C \cdot I_{cl} \cdot t_{on} \quad (4)$$

$$t_{on} = \Delta V \cdot C/I_{cl}$$

Further,

$$V_o - (V_o - \Delta V) = 1/C \cdot I_{d1} \cdot t_{off} \quad (5)$$

$$t_{off} = \Delta V \cdot C/I_{d1}$$

From equations 2, 3, 4 and 5, equation 1 becomes

$$V_{eff,1} = V \cdot \sqrt{I_{d1}/I_{d1} + I_{cl}} = \sqrt{R \cdot (1/R + 1/r) \cdot V_o V} \quad (6)$$

Thus, in the output voltage controlling circuit of FIG. 4 when the input voltage is changed, the output effective-voltage $V_{eff,1}$ is also varied and the output square-wave does not have a stabilized effective-voltage.

Next, the effective-voltage of the square-wave output appearing at the output terminal 8 in the output voltage compensating circuit of FIG. 5 $V_{eff,2}$ is calculated in the similar manner. When the voltage at the terminal 48 is in the neighborhood of V_o and the output transistor circuit 10 is conductive, the charging current I_{c2} flowing into the capacitor 45 is

$$I_{c2} = [(V - V_o)/R] - [(r_2 + \rho) \cdot V_o - r_2 \cdot V] / [r_1 \cdot r_2 + (r_1 + r_2) \cdot \rho] \quad (7)$$

The discharging current I_{d2} flowing from the capacitor 45 when the output transistor circuit 10 is cut off, is

$$I_{d2} = [(r_2 + \rho) \cdot V_o - r_2 \cdot V] / [r_1 \cdot r_2 + (r_1 + r_2) \cdot \rho] \quad (8)$$

From equations 4 and 5, the effective-voltage $V_{eff,2}$ is

$$V_{eff,2} = \sqrt{[r_2 / r_1 \cdot r_2 + (r_1 + r_2) \cdot \rho] \cdot V_o} / \sqrt{[1 + \rho/r_2] \cdot V_o - V} / [V - V_o] \cdot V^2 \quad (9)$$

As is apparent from the comparison of equations 6 and 9, according to equation 6 $V_{eff,1}$ monotonically increases with the increase in V , whereas according to equation 9 variation in $V_{eff,2}$ can be made zero or extremely small within the practical range of input voltage V .

Namely, when it is assumed that $\rho/r^2 = 8$ and the quantity in the root in the second term on the right hand side of equation 9 is set to be W ,

$$W = (9 V_o - V) / (V - V_o) \cdot V^2$$

Differentiation of W with respect to V gives

$$dW/dV = [-2 V(V - 3V_o)^2] / [(V - V_o)^2]$$

Thus, W has a flexion point at $V = 3V_o$.

In the neighborhood of $V = 3V_o$ the variation of W is extremely small and the effective-voltage of the square-wave output is substantially constant. Hence, the circuit shown in FIG. 5 can be used as an effective-voltage stabilizer device.

In an example device of the above stabilizer according to the present invention, the values of R , r_1 , r_2 , ρ , V_o were selected as $47 k\Omega$, $40 k\Omega$, 340Ω , 5Ω , $3.5 V$, respectively. The resultant effective-voltage was as shown in the input voltage-output effective-voltage characteristic curve of FIG. 7. In the range where the input voltage V was from about $10 V$ to about $20 V$, the

output effective-voltage V_{eff} became almost constant. This range corresponds to the practical range of the effective-voltage stabilizer of the present example.

According to this effective-voltage stabilizer, a contactless transistor type voltage stabilizer capable of providing a square-wave output can be achieved, power consumption in a transistor can be decreased to reduce the cost, and loads such as a meter connected to this stabilizer can be operated with high precision by stabilizing the effective-voltage of the square-wave output.
